US0D1082310S

(12) United States Design Patent (10) Patent No.: US D1,082,310 S
(45) Date of Patent: * Jul. 8, 2025

(54) STORAGE BOX

(71) Applicant: Xinfuqiang Travel Stationery Products (Shenzhen) Co., Ltd., Shenzhen (CN)

(72) Inventor: Huiqiang Luo, Fenggang County (CN)

(73) Assignee: Xinfuqiang Travel Stationery Products, Shenzhen (CN)

() Term: 15 Years

(21) Appl. No.: 29/986,442

(22) Filed: Jan. 17, 2025

(51) LOC (15) Cl. 03-01

(52) U.S. Cl.

USPC D3/289

(57) CLAIM

The ornamental design for a storage box as shown and described.

DESCRIPTION

FIG. 1 is a perspective view of a storage box showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view thereof in an open configuration.

The broken line depicts portions of the storage box that form no part of the claimed design.

1 Claim, 9 Drawing Sheets
